UNITED STATES PATENT OFFICE

JAMES P. FISHER, OF BARTLESVILLE, OKLAHOMA, ASSIGNOR, BY MESNE ASSIGNMENTS, TO BURGESS-PARR COMPANY, OF MOLINE, ILLINOIS, A CORPORATION OF DELAWARE

GAS CALORIMETER

Application filed March 9, 1928. Serial No. 260,465.

The present invention relates to gas calorimeters and more particularly to those adapted to determine the heat value of gas from a gas source in a non-intermittent manner.

It has been proposed to measure and record the calorific value of gas from a gas source in a non-intermittent manner. This method of determining the calorific value however involves pumping proportional quantities of gas and water for considerable periods of time and difficulties have been encountered in obtaining satisfactory mechanism for this purpose. It is one of the objects of the present invention to provide simple and reliable mechanism for pumping predetermined portions of gas and water.

Further objects and advantages of the present invention will be clear to those skilled in the art from the following description taken in connection with the accompanying drawings, in which:

Fig. 1 is an elevation of a calorimeter apparatus including mechanism according to the present invention;

Fig. 2 is a detail elevation of a portion of the apparatus illustrated in Fig. 1;

Fig. 3 is a section taken on the line 3—3 of Fig. 2 looking in the direction of the arrows;

Fig. 4 is a partial side elevation of a portion of the apparatus shown in Figs. 2 and 3;

Fig. 5 is an elevation of another portion of the apparatus illustrated in Fig. 1;

Fig. 6 is a section on a line 6—6 of Fig. 5 looking in the direction of the arrows;

Fig. 7 is an elevation view in detail of the pumping mechanism shown in Fig. 1, parts being broken away and parts being shown in section for purposes of illustration.

In the apparatus illustrated in the drawing, gas whose heating value is to be determined is introduced into the apparatus through the valve 10 in pipe 12. It is common practice to determine the heating value of gas by measuring the temperature rise of a given amount of water produced by burning a given quantity of gas under standard conditions of temperature and pressure. Water for use in determining the calorific value of the gas may be introduced into the apparatus

through the valve 14 in the pipe 16. It has been proposed to compensate the apparatus for varying changes in pressure and temperature of a gas, but I prefer to maintain the density of the gas constant, and for this purpose a varying amount is wasted from the pipe 12 to maintain a constant density at the point the gas is metered to the burner. The mechanism for this purpose includes a waste pipe 18 connected to the pipe 12, pipe 18 having a waste controlling and pressure controlling mechanism 20 connected therein. The specific embodiment of pressure controlling mechanism 20 illustrated in the drawing includes a section of rubber tubing 22 connected into the pipe 18, means being provided in connection with tubing 22 whereby it acts as a pinch valve. For this purpose, the mid-portion of tubing 22 has its edges clamped by a cut-away clamp block 24 and a bar 26 (as illustrated in Fig. 4) so that the natural resiliency of the tubing 22 exposed by the cut-away portion of the clamp block 24 is free to expand to a certain amount thereby providing a restricted waste passage 28 for the escape of gas. In the arrangement illustrated, the size of passage 28 is restricted automatically to the desired degree to maintain the desired density in pipe 12. The means for restricting the passage 28 includes a spindle 30 entering the cut away part of block 24. One end of spindle 30 is in contact with the surface of the tube 22 in the center of block 24, and the longitudinal position of spindle 30 is determined by a diaphragm 34. Diaphragm 34 is subject on one side to the pressure of gas in pipe 18 and on the other side to a pressure varying with the temperature of the water delivered by pipe 16 to maintain the density constant at a point in the apparatus at which the gas and water are at the same temperature. The diaphragm 34 is mounted in a casing 36, the edges of the diaphragm being clamped between two portions of the casing. On one side of diaphragm 34 is a chamber 38 connected to the pipe 18 through the nipple 40 on the inlet side of the passage 28. On the other side of the diaphragm 34 is a closed chamber 42, formed by diaphragm 34 and a metal cup 44, and containing a fixed weight 100

of gas. Since chamber 42 contains a fixed weight of gas and is of fixed volume, the absolute pressure of the gas in chamber 42 will vary directly with its absolute temperature. 5 The spindle 30 has its end opposite tube 22 resting against the diaphragm 34 so that the size of passage 28 and the pressure in pipe 18 and pipe 12, is regulated by the diaphragm 34. The slight resiliency of the tubing 22 where it presses against spindle 30 is preferably taken up by adjusting the position of the diaphragm. A small flexible diaphragm 46 surrounding spindle 30 forms an opening in the casing permitting the spindle to pass 10 through it so that the movement of the diaphragm 34 may be transmitted outside of casing 36 without leakage of gas. For any constant temperature, the gas in this chamber will exert a constant pressure against the diaphragm 34. The opposite face of diaphragm 34 being subject to gas pressure from pipe 18, the position of the diaphragm will vary with variations in pressure of the gas. It will be seen that as the pressure of gas in pipes 12 and 15 18 increases, the pressure against diaphragm 34 in chamber 38 also increases thereby moving the diaphragm 34 in the direction to permit the passage 28 to enlarge and thereby increase the escape of gas from the pipe 12. 20 Increasing the escape of gas evidently reduces the pressure in the pipe 12. On the other hand, if the pressure in pipe 18 decreases, pressure in chamber 38 also decreases thereby causing spindle 30 to restrict the passage 28 25 and to thereby build up pressure in pipes 18 and 12. It will be seen therefore that the valve mechanism 20 together with its manner of connection to pipe 12 is such as to maintain a constant pressure in the pipe, so long as the 30 temperature of the gas in chamber 42 is constant. If the temperature in chamber 42 varies, the pressure in pipe 12 will be automatically varied by an amount proportional to the change in absolute temperature where- 35 by the gas will be at constant density when brought to the temperature of the gas in chamber 42, which is the same as the water temperature. It is preferred that gas escap- 40 ing through pipe 19 be burned as indicated at 49. The escaped gas is thereby prevented from becoming a nuisance, and moreover the quantity of gas being wasted is made evident to the operator, who can therefore regulate the valve 10 to maintain a low rate of gas 45 wastage.

The temperature of the gas in chamber 42 is maintained the same as the temperature of the gas being metered in meter 52 by the stream of water fed to the calorimeter 60 through pipe 16. Part of this water is wasted and part of it passes through the meter 52 to the calorimeter. It is desirable to maintain a temperature of this water near that of the room so there will be no substantial change 65 in temperature between chamber 42 and meter 52. A heater diagrammatically indicated at 50 and which can be automatically controlled can be provided to maintain the water temperature at room temperature, or if desired, it can be maintained at any constant 70 value. There would be a slight advantage in maintaining this temperature constant as the humidity of the gas passing through meter 52 is thereby maintained constant. However, in perhaps the majority of localities, the 75 variations of room temperature and water temperature are sufficiently small that the heater 50 may be omitted without materially disturbing the condition of constant density of the gas at the outlet of the meter which is 80 the critical feature of the present invention.

In continuous acting calorimeter apparatus, it is necessary to supply the calorimeter proper with water and gas in constant proportions. In the embodiment of the invention 85 illustrated in the drawing, the gas and water for the calorimeter proper are measured and pumped by a pumping mechanism indicated in general by reference character 52. Pumping and measuring mechanism 52 is illustrated in detail in Fig. 7 and includes inlet chamber 54. The gas from pipe 12 is conducted to chamber 54 through a pipe 56, pipe 56 enter- 90 ing chamber 54 at the top. Water pipe 16 also enters chamber 54 as appears in Fig. 7. The pumping mechanism withdraws gas and water from chamber 54 and the proportion of water volume to gas volume so withdrawn depends upon the water level in the chamber 95 54. It is desired therefore to maintain the water level in chamber 54 at a predetermined adjustable level. For this purpose a vertical overflow pipe 58 is provided. In the arrangement illustrated, pipe 58 enters the bottom of the chamber 54 through the stuffing 100 box 60. It is evident that the horizontal upper edge 62 of the pipe 58 determines the water level in chamber 54 and the position of the edge 62 can be adjusted by sliding the pipe 58 in the stuffing box 60. Water over- 105 flowing through the pipe 58 may be run to waste as indicated at 64. The pipe 58 contains a trap 65 to prevent escape of gas at 64. Moreover, the discharge point at 64 is prefer- 110 ably visible so that the amount of water run- 115 ning to waste can be regulated.

The pumping mechanism 52 preferably includes a pumping element of the screw type comprising an outer barrel or shell 66 within which is a screw comprising a shaft 68 hav- 120 ing one or more threads 70 thereon extending from shaft 68 to the inner surface of the barrel 66. Preferably the screw is of the double thread type as illustrated. Preferably also the outer edges of the screw-threads are fixed 125 to the barrel and revolve therewith. In the arrangement illustrated, the barrel 66 is partially closed by end rings 72, 72, each of which has a beveled face 74 acting as journals on which the barrel revolves when in use. The 130

rotation of the barrel 66 causes the threads therein to withdraw water and gas from the chamber 54 and to discharge it into a similar chamber 76 at the other end of the screw. It will be noted that mechanism 52 cannot abstract gas from chamber 54 unless the water level in the mechanism is at least as high as the lower edge of shaft 68. The diameter of shaft 68 therefore determines the permissible amount of variation of the water level in the mechanism 52 and therefore determines the possible variation in the ratio of water and air pumped by the mechanism in a given amount of time. It is preferred therefore that the diameter of shaft 68 be at least twice the height of the thread or threads 70 as is the case in the device illustrated in the drawing. The chambers 54 and 76 have beveled faces complementary to the journals 74 and 20 acting as bearings therefor. The chambers 54 and 76 together with barrel 66 may conveniently be mounted by pins 78, 78 in a frame 80 in which is carried a motor 82 having a worm drive including a gear 84 fixed on the barrel 66 for revolving the barrel when the motor is running.

Water and gas are withdrawn from chamber 76 and conducted therefrom to the calorimeter proper. Water is taken from chamber 76 through the vertical outlet pipe 86 which enters the bottom of the chamber 76 through the stuffing box 88. The horizontal upper edge 90 of pipe 86 should be at substantially the same level as the upper edge 62 of pipe 58 so that the water level in chambers 54 and 76 will be substantially the same. For this purpose, outlet pipe 86 is made adjustable in stuffing box 88. Gas is withdrawn from the chamber 76 through the pipe 92 entering chamber 76 through the top. It is essential that the pressure of the gas in pipe 92 and in chamber 76 should be substantially the same as that in pipes 12 and 56 and chamber 54. In order to maintain the equality of pressure mentioned, a regulating valve 94 is connected into pipe 92. Valve 94 is of a type somewhat similar to the valve mechanism 20 previously described. Valve 94 as illustrated includes a rubber tubing 96 forming a pinch valve of the type previously described in connection with mechanism 20. Valve mechanism 94 includes also a casing 98 within which is mounted a diaphragm 100. The edges of the diaphragm 100 are clamped by the edges of the casing 98, the diaphragm thereby dividing the interior of the casing into two chambers. On one side of the diaphragm 100, casing 98 is connected to the pipe 92 through a nipple 102. The chamber 55 in casing 98 on the other side of diaphragm 100 is connected through pipe 104 to the pipe 12. A pin or spindle 106 moreover transmits movements of the diaphragm 100 to the constricted portion of the tubing 96 so as to regulate the amount of gas flowing there-

through. It will be evident from the previous description of the valve mechanism 20 that the valve 94 will operate to maintain the pressure in the pipe 92 substantially equal to that in pipe 12. It will be noted that the pressure connection 102 to the side of the diaphragm 100 connected to pipe 92 is similar to the arrangement of valve mechanism 20, on the inlet or upstream side of the valve.

The pipes 86 and 93 conduct the gas and water to the calorimeter proper indicated at 108. The calorimeter 108 illustrated in the drawing is assumed to be of the well-known Junkers type and therefore needs no further description. The calorimeter, however, may be of any convenient type within the present invention. In the arrangement illustrated the gas is burned at 110. The calorimeter is illustrated as having mercury thermometers 112, 112 and also a continuous resistance differential thermometer 114 located in the water of the calorimeter at the sides thereof. The electrical temperature differential recording mechanism is diagrammatically illustrated as 116. The function of the calorimeter proper and the temperature indicating and recording mechanism may be the same as for any calorimeter of this type and need not be described.

The functioning of each feature of the calorimeter can be calibrated at any time by instruments ordinarily available. At any time, the gas passing to the calorimeter burner can be diverted through a standard measuring device such as a standard meter or cu. ft. bottle and the amount of water passing through the calorimeter for the same period of time can be caught and measured or weighed. The gas volume as measured can be reduced to standard barometer and temperature conditions and compared with the weight of water passed. The functioning of the standardizing regulator or valve 20 can be checked at any time by observing the pressure on the gas passing through the pumping and measuring device 52. This pressure can be observed by an ordinary manometer. The temperature of the standardizing regulator 20 can be observed by a mercury thermometer and this value can be compared with the value for which the calorimeter was standardized. The functioning of the regulator valve 94 in maintaining equal pressures on the two sides of pump or meter 52 can be checked by connecting a U-tube to the pipes 56 and 92. The temperature recording apparatus 114 can be checked by the mercury thermometers.

It will be obvious that the correct functioning of the apparatus herein disclosed is dependent upon the capacity of the valve mechanism 20 to properly control the pressure in the pipe 12. A given mechanism 20 can maintain the constant density of the gas

at the outlet of meter 52 only within certain variations in the effective pressure of the gas supply, and variations in temperature of the water supply. Regulating valve mechanism 20 can operate only to reduce the pressure in pipe 12 and it is evident that the pressure in pipe 12 can never be reduced below that of the atmosphere for the reason that waste pipe 19 discharges to the atmosphere. It is therefore necessary to choose the weight of gas in chamber 42 so that it shall have a density sufficient to maintain the gas pressure in pipe 12 a little above atmospheric pressure at any temperature of water that will be encountered. Obviously this requirement will be different at different altitudes. It is not probable, however, that a given instrument will be required to operate at various altitudes or in various general climatic conditions, but if an instrument is designed for one climate and then moved to quite a different one, it may be necessary to cool or heat the water passing to chamber 48 of valve mechanism 20, although, in general, the heater 50, if used, is not essential. For a location and climate similar to that of Bartlesville, Oklahoma, it is considered satisfactory to make the weight of the gas in chamber 42 such as to give a pressure of thirty inches of mercury at 60° F., since the barometer in Bartlesville is always less than thirty and it is not probable that the room temperature or water temperature of the instrument would fall below sixty degrees F. In designing an apparatus for a colder climate, it might be well to increase the density of the gas in chamber 42 somewhat, say to 110% of the 30-60 condition. The chamber 42 having been sealed, the absolute pressure in the chamber varies as the absolute temperature. Assuming that the chamber 42 has been filled with gas and sealed under conditions of thirty inches of mercury pressure and 60 degrees F. temperature, if the cooling water should reach a temperature of 100° F., the pressure in chamber 42 would be 32.3" and the pressure in pipe 12 could not fall below this. The apparatus might not function properly under this condition and it might be necessary to cool the water entering through pipe 16. However, a tap water temperature of 100° F. probably will never be encountered in Bartlesville, Oklahoma. A tap water temperature of 90° F. is not improbable, but there is no reason to suppose that the apparatus would not perform satisfactorily at this temperature. The foregoing discussion assumes that the gas supply to pipe 12 is restricted sufficiently so that the valve mechanism 20 can always reduce the pressure in pipe 12 to the required degree to maintain constant density at the outlet of the meter 52, or at least so that the pressure in pipe 12 shall be as low as that in chamber 42.

In putting the apparatus, according to the present invention, into operation, it is necessary to adjust gas cock 10 and water cock 14 to furnish a slight excess of both gas and water to the instrument more than will be handled by the gas and water measuring pump 52. Pump 52 in conjunction with automatic valves 20 and 94 will extract both gas and water from chamber 54 at constant rates. The surplus water will overflow and be visible at 64 and the surplus gas will be released by valve 20 and if ignited at 49, will be visible evidence that a reasonable surplus is being supplied. If flame 49 goes out, it is evidence that gas is not being supplied to chamber 54 as fast as the action of the pump 52 removes it and cock 10 must be opened until a flame is obtained at 49 with meter 52 operating. If opening cock 10 does not give a flame at 49, it shows that the pressure of gas supply is lower than that required to bring the density to standard at the temperature of the water in 48 and 52. In this case the pressure on the gas supply must be increased or the temperature of the water supply reduced until the valve 20 again will release a surplus of gas at 49. When a small flame is burning at 49 and a small stream of water wasting at 64, with meter 52 operating, the gas and water supplies to the instrument are sufficiently well regulated.

In building an apparatus according to the present invention, it is considered satisfactory to make tubes 22 and 26 of ordinary soft rubber laboratory tubing of about $\frac{3}{8}$ inch diameter and $\frac{1}{4}$ inch bore. The water and gas overflow pipes should be selected of sufficient size that no back pressure shall be placed on gas escape passage 28 and that there shall be sufficient weir surface at point 62. Pipe 86 should, of course, be the same size as pipe 58. The remaining pipes can be made satisfactorily and conveniently of $\frac{3}{8}$ inch outside diameter copper or brass tubing or with $\frac{1}{8}$ inch or $\frac{1}{4}$ inch iron or brass pipe.

In ordinary practice with natural gas, the Junkers calorimeter burns about $\frac{1}{10}$ of a cubic foot of gas per minute and the water is adjusted to secure a temperature rise of about 15 degrees Fahrenheit. This temperature rise requires about seven pounds of water per minute. One tenth of a cubic foot of water weighs 6.25 pounds. It is evident therefore that pipes 58 and 86 should be set so that meter 52 will deliver substantially equal volumes of gas and water when the present apparatus is operating on natural gas. In other words, the tops of pipes 58 and 86 should be set approximately at the level of the axis of rotation of barrel 66. When obtaining the calorific value of manufactured gas, the volume of gas space in meter 52 should be relatively larger and the pipes 58 and 86 should be adjusted accordingly.

Diaphragms 34 and 100 preferably are rather deeply corrugated and made from very thin metal preferably copper and they should be adjusted to operate near their normal or flat position. This adjustment can be made by selecting pins 30 and 106 of proper length and by selecting the proper amount of gas to be held in chamber 42.

It will be seen from the foregoing that, according to the present invention, provision has been made for continuous automatic operation in which gas and water will be measured accurately into a Junkers or other type calorimeter. The proportion between the volume of gas and the volume of water can be set at will within certain limits, and when once set will remain constant. Since the density of the gas is maintained constant the ratio between the amount of gas and water will remain constant. This ratio can be made 1 volume of gas to 1 volume of water or two volumes of gas to 1 of water, or any other desirable ratio.

The gas will be measured at an automatically controlled pressure a little above atmospheric pressure, this pressure variation being maintained automatically so that the same weight of gas will be put through the metering element 52 per revolution regardless of changes in barometric pressure (and atmospheric temperature). This pressure can be arranged to correspond to any desired standard of measurement as 30 inches of mercury (and 60° F.), or preferably some fixed number of times the standard, as for instance, 110% of 30 inches, (60° F. conditions). Moreover, as the mass of gas is small in comparison to the mass of water passing through the meter 52 and as the gas is in contact with the water and with the threads 70 and shaft 68 which pass alternately through the water and the gas, the gas is measured at the temperature of the water going through the meter and at a pressure automatically controlled by valve 20 to correspond with that temperature to give a constant density of the gas being measured. This insures a constant ratio between the amount of gas and amount of water pumped by the meter 52 to the calorimeter.

Means is also provided whereby the pressure is balanced across the metering device so that the meter 52 will at all times operate against zero pressure differential and its volumetric capacity is therefore fixed and reliable. After the gas has been measured it passes through a regulator before going to the calorimeter burner, so that the variations in size in the orifice in the burner will have no effect on the measurement of the gas. The calorimeter element proper can be an ordinary Junkers type calorimeter with the usual mercury observation thermometers. In addition to these mercury thermometers a differential recording thermometer 116 or

any other type of instrument for measuring the difference in temperature can be applied and this difference of temperature will be directly proportional to the heating value of the gas passing through the instrument and can be recorded directly as heating value of the gas. As above noted, the gas passing from the metering element is maintained at constant density. As it is metered in contact with the water passing to the calorimeter proper, its humidity is also maintained constant if the water temperature is constant and there need be no correction device whatever applied to the temperature recording or indicating instrument, and the simplest and cheapest reliable type of recording or indicating instrument available may be used.

It will be noted that the design of the gas and water metering element involves a very small volume of gas trapped in the metering device. The special design metering device to keep this volume small is one main feature of the present calorimeter, as a small volume of gas passing through the calorimeter reduces the time lag between a change in the calorific value of the gas and its indication. All gas passages from the intersection of pipes 12 and 18 through to the burner at 10 are preferably kept at a minimum length and cross-section to assist in minimizing the time lag of the instrument. There is, therefore, according to the present invention, a minimum lag between a given change in the calorific value of the gas and the recording or indication of said change by the present apparatus.

The apparatus according to the present invention therefore permits the control of a gas bench, or the like, to a maximum advantage. In this connection, it has been found that the volume of gas in the metering mechanism plus that in the connections between the metering mechanism and the burner of the calorimeter is much less than in the ordinary continuous calorimeter.

Having thus described my invention, I claim:

1. The combination in a calorimeter apparatus, of a pump metering gas and water in fixed proportions by volume, a combined gas and water chamber at the intake side of said pump, a pressure regulator acting on the gas flowing to said chamber, a combined gas and water chamber on the outlet side of said pump, and a pressure regulating valve acting on the gas flowing from said second chamber.

2. The combination as stated in claim 1 and in which the pressure regulating valve acting on the gas flowing from the pump outlet maintains a pressure on the pump outlet equal to the pressure at the pump inlet.

3. The combination as stated in claim 1 in which the pressure regulating valve acting on the gas flowing from the pump outlet maintains a pressure on the pump outlet equal

to the pressure at the pump inlet and in which the pressure regulating valve acting on the gas flowing from the second chamber includes an operating diaphragm one side of which is subject to pressure from the chamber on the intake side of the pump.

4. The combination as stated in claim 1 in which the pressure regulating valve acting on the gas flowing from the pump outlet 10 maintains a pressure on the pump outlet equal to the pressure at the pump inlet, in which the pressure regulating valve acting on the gas flowing from the second chamber includes an operating diaphragm one side of which is subject to pressure from the chamber on the intake side of the pump, and in which the diaphragm of the pressure regulating valve acting on the gas flowing from the pump outlet is subject on its other side to the pressure 20 of gas on the inlet side of the valve of which it is a part.

5. The combination in a calorimeter apparatus, of two combined gas and water chambers and a pump intermediate said chambers 25 and metering gas and water from one to the other, said pump including a screw thread and a shaft on which said thread is mounted, said shaft having a diameter relatively large as compared to the height of the screw thread.

6. The combination in a calorimeter apparatus, of two combined water and gas chambers and a pump intermediate said chambers and metering gas from one to the other, said pump having a barrel mounted 30 for rotation, a screw thread within said barrel and in contact with the inner face thereof, and a shaft contacting with and surrounded by said thread.

7. The combination as stated in claim 6 and 40 in which said barrel is journalled on said chambers.

8. The combination in a calorimeter apparatus of a pump metering gas and water in fixed proportions by volume and a pressure regulating valve acting on the gas flowing to said pump to automatically vary the pressure in the pump to maintain the density of the gas constant on the pump outlet.

9. The combination in a calorimeter apparatus of a pump metering gas and water in fixed proportions by volume and a pressure regulating valve acting on the gas flowing through said pump, the said pressure regulating valve comprising a closed chamber containing gas, said chamber having a heat transferring wall, and an operating diaphragm forming one side of said chamber; and connections for flowing water passing to the pump in contact with said heat transferring wall.

In testimony whereof I affix my signature.
JAMES P. FISHER.
